Filed June 28, 1961, Ser. No. 120,339

5 Claims. (Cl. 208—95)

The present invention relates to a process for the catalytic reforming of hydrocarbons and various mixtures of hydrocarbons. More specifically, the present invention is directed toward the solution of a particular problem arising as the result of the necessity to produce a motor fuel gasoline having rigid specifications in regard to octane rating and volatility, imposed thereupon. The method of the present invention involves the fractionation of a catalytically reformed liquid product effluent, with subsequent blending of the resulting fractions in such a manner as results in a final product of the desired quality.

Rigid specifications have been expressly imposed upon motor fuel gasolines for utilization in the European market. These specifications require the production of a high octane gasoline possessing an unusually high degree of volatility. The octane rating required is of the order of about 98.0 to 100.0, or more (F-1 Clear); the volatility factor, being a measure of the quantity of hydrocarbons within the motor fuel which are distillable at a temperature below 212° F., is required to be at a minimum of about 45.0%, and preferably as high as 50.0% by volume. A motor fuel, or aviation gas, having these characteristics is particularly required in normally cold climates where engine start-up is difficult to achieve with standard high octane fuel having only normal volatility.

Of the various types of hydrocarbons normally present in a motor fuel gasoline, paraffins, olefins, naphthenes, and aromatics, the aromatic hydrocarbons possess the highest octane blending values, and, in order to produce a motor fuel having an octane rating in excess of about 98.0, at least 58% by volume of aromatics is required. Similarly, for an octane number of 100, at least 62% of aromatic hydrocarbons are required. Many processes are currently available for the conversion of petroleum hydrocarbons into relatively high octane gasolines, such processes including thermal cracking, catalytic reforming, catalytic cracking, alkylation, etc. The catalytic reforming of petroleum hydrocarbons affords the greatest opportunity to produce a final product highly concentrated in aromatic hydrocarbon, and is, therefore, widely utilized throughout the petroleum industry. However, notwithstanding the applicability of a catalytic reforming process, the foregoing rigid specifications as to octane rating and volatility are so inconsistent with each other, that the required product quality is virtually unattainable. All of the aromatic hydrocarbons, possessing the highest octane blending values, have normal boiling points above about 212° F., with the exception of benzene which has a normal boiling point of about 176° F. As stated above, between about 58.0% and about 62.0% by volume of aromatics are required to give an octane rating in excess of about 98.0. Since benzene is not formed nearly to the extent of other aromatics, it is evident that on the one hand the specifications require that at least 45.0% of the gasoline be distillable below a temperature of 212° F.

2

(by standard ASTM distillation methods), while on the other hand, the gasoline must consist of some 60.0% by volume of aromatics, most of which boil above 212° F. in order to meet the requirement directed toward the octane rating. Notwithstanding that aromatic hydrocarbons have the tendency to form azeotropic mixtures with paraffins, resulting in a lowering of the boiling point thereof, extreme difficulty exists in reconciling the foregoing contrary requirements.

10 The object of the present invention is to provide a solution to the rather complex problem hereinabove set forth. I have found that a motor fuel gasoline, having characteristics which far exceed the foregoing rigid specifications, is readily obtainable through a combination process involving catalytic reforming and detailed fractionation.

15 Therefore, in a broad embodiment, the present invention relates to a process for producing high octane gasoline of which at least about 45.0% by volume is distillable at a temperature below 212° F., which process comprises fractionating a high octane, catalytically reformed product effluent of lower volatility into a first fraction obtained at a cut-point less than about 90° C., a second fraction obtained at a cut-point less than about 120° C. and a third, bottoms fraction; combining at least a portion of said first fraction with at least a portion of said second fraction to yield a high octane mixture of which at least about 45.0% by volume is distillable below a temperature of 212° F., and combining the remainder of said first and second fractions with said third bottoms fraction to yield a high octane blending stock of lower volatility.

20 In another broad embodiment, the present invention involves a process for producing a high octane gasoline of which at least about 45.0% by volume is distillable below a temperature of 212° F., which process comprises fractionating a high octane, debutanized catalytically reformed product effluent of lower volatility into a first fraction obtained at a cut-point less than about 90° C. and substantially free from toluene, a second fraction obtained at a cut-point less than about 120° C. and containing substantially all the toluene initially present in said debutanized reformed product effluent, and a third, bottoms fraction; combining at least a portion of said first fraction with at least a portion of said second fraction in which the blended ratio of said first fraction to said second fraction is less than that in which they were initially present in said debutanized reformed product effluent, to yield a high octane mixture of which at least about 45.0% by volume is distillable below a temperature of 212° F., and combining the remainder of said first and second fractions with said third bottoms fraction to yield a high octane blending stock of lower volatility.

25 A limited embodiment of the present invention is directed toward a process for producing a gasoline having an F-1 Clear octane rating in excess of about 98.0, at least 45.0% by volume of which gasoline is distillable at a temperature below 212° F., which process comprises fractionating a debutanized catalytically reformed product effluent, of which less than about 45.0% by volume is distillable at a temperature below 212° F., into a first fraction obtained at a cut-point of about 85° C. to about 90° C. and substantially free from toluene, a second fraction obtained at a cut-point of about 110° C. to about 120° C. and containing substantially all the toluene initially present in said reformed product, and a third bottoms fraction substantially free from toluene; combining

at least a portion of said first fraction with at least a portion of said second fraction in a volumetric ratio less than that in which they were initially present in said debutanized, catalytically reformed product, the resulting mixture having an octane rating in excess of about 98.0, and of which at least 45.0% by volume is distillable at a temperature below 212° F., and combining the remainder of said first and second fractions with said third bottoms fraction to yield a high octane blending stock of which less than about 45.0% by volume is distillable at a temperature below 212° F.

The present invention is particularly directed toward a combination of catalytic reforming and detailed fractionation for producing high octane gasoline having high volatility. The combination process involves catalytically reforming a low octane hydrocarbon mixture of low volatility at reforming conditions selected to produce a debutanized liquid product effluent having an octane rating in excess of about 98.0 (F-1 Clear), of which liquid product less than about 45.0% by volume is distillable at a temperature below 212° F., fractionating said product effluent into a first fraction obtained at a cut-point less than about 90° C. and substantially free from toluene, a second fraction obtained at a cut-point less than about 120° C. and containing substantially all the toluene initially present in said reformed product effluent, and a third, bottoms fraction; combining at least a portion of said first fraction with at least a portion of said second fraction in a volumetric ratio less than that which they were initially present in said catalytically reforming product, the resulting mixture having an octane rating in excess of about 98.0 and of which at least 45.0% by volume is distillable below a temperature of 212° F., and combining the remainder of said first and second fractions with said third bottoms fraction to yield a high octane blending stock of which less than about 45.0% is distillable at a temperature below 212° F.

From the foregoing embodiments, it is readily ascertained that I have found a method to produce a motor fuel having characteristics far exceeding the rigid specifications imposed thereupon. The high octane, highly volatile gasoline of the present invention is prepared by fractionating a debutanized catalytically reformed product effluent into three distinct fractions: (1) a "pre-toluene" fraction, (2) a "toluene" fraction, and (3) a "post-toluene" fraction. By combining the "pre-toluene" and "toluene" fractions in a volumetric ratio which is less than that in which they were initially present within the catalytically reformed product, there results a gasoline possessing the requisite high octane rating as well as the unusually high volatility factor, as measured by the volume percent thereof which is distillable at a temperature below 212° F. in accordance with Standard ASTM distillation methods. As stated in the foregoing embodiments, the remaining portions of the "pre-toluene" and "toluene" fractions may be recombined with the "post-toluene" fraction to yield a high octane blending stock suitable for utilization in the production of "pool" gasoline.

The means by which the detail fractionation is combined with a catalytic reforming process, is illustrated in the accompanying drawing. With reference to the drawing, it is noted that the present invention is readily separated into its component parts, a reaction section which encompasses a catalytic reforming unit, and a fractionation section. The charge stock, for example, a semi-heavy naphtha having an initial boiling point of about 200° F. and an end boiling point of about 350° F. (by ASTM 100 ml. distillation), and having a relatively low octane rating, is passed through line 1 into heater 2, to be raised to the desired operating temperature. Prior to entering heater 2, the liquid charge is admixed with internally recycled hydrogen in line 3, in an amount to result in a hydrogen to hydrocarbon mol ratio within the range of from about 5.0 to about 20.0. The heated

mixture, at a temperature within the range of about 800° F. to about 1100° F., passes through line 4 into reforming reactor 5 at a liquid hourly space velocity, defined as volumes of hydrocarbon charge per volume of catalyst disposed within the reaction zone, of about 0.5 to about 10.0. Reactor 5 is maintained under an imposed pressure within the range of about 300 to about 1500 pounds per square inch, and has disposed therein a suitable reforming catalyst comprising metals selected from the platinum group of the periodic table. Suitable reforming catalysts comprise platinum, palladium, osmium, iridium, ruthenium, rhodium, mixtures of two or more, etc., composited with a suitable refractory inorganic oxide carrier material. It is understood that the precise composition of the catalyst, and the concentrations of the various catalytically active metallic components, are not essential to the combination process of the present invention. Both the catalyst disposed in reactor 5, and the operating conditions imposed therein, are selected to result in a catalytically reformed liquid product effluent having an octane rating in excess of about 98.0, F-1 Clear.

The total reactor 5 effluent is withdrawn through line 6, passing into separator 7 from which a hydrogen-rich recycle gas stream is withdrawn through line 8 via compressor 9, discharging through line 3 to be admixed with the fresh hydrocarbon charge in line 1. At least a portion of the recycle gas is withdrawn from the process through line 10 containing pressure control valve 11. Normally liquid hydrocarbons are withdrawn from separator 7 through line 12, passing into stabilizer 13. The operating conditions imposed upon stabilizer 13 are such that the column may function as a debutanizer, the C₁ to C₄ hydrocarbons being withdrawn as an overhead gaseous product through line 14, or as a depropionizer, such that the butanes are retained in the bottoms fraction leaving via line 15, or to include any portion of the C₄ hydrocarbons present in the reactor 5 effluent, in the "debutanized" liquid product leaving stabilizer 13 via line 15.

The catalytically reformed liquid product effluent is passed into toluene fractionator 16, containing center-well 17. The reformed product effluent is fractionated into three individual fractions; the first fraction, "pre-toluene," is obtained as an overhead product in line 18 at a cut-point less than about 90° C. and preferably within the range of about 85° C. to 90° C. The middle, "toluene" fraction is removed via line 20 from above center-well 17, and is obtained at a cut-point less than 120° C. and preferably within the range of about 110° C. to about 120° C. The third fraction, or the "post-toluene" bottoms fraction, is removed from toluene fractionator 16 via line 22, and is substantially toluene-free. Both the "pre-toluene" and "toluene" fractions are transmitted to storage tanks 19 and 21 respectively, from which predetermined quantities are withdrawn via lines 23 and 24 respectively, combining in line 25 to yield a high octane (greater than 98.0 F-1 Clear), highly volatile (45.0% by volume of which boils at a temperature below 212° F.) motor fuel gasoline. The remaining portions of the "pre-toluene" and "toluene" fractions are withdrawn from the storage tanks via lines 26 and 27 respectively, being combined with the "post-toluene" fraction in line 22 to yield a high octane blending stock suitable for utilization in "pool" gasoline.

The following example is given for the purpose of indicating the benefits to be afforded through the utilization of the process of the present invention as hereinbefore described with reference to the accompanying drawing. The catalyst employed in the example was a composite of $\frac{1}{16}$ -inch alumina spherical particles combined with 0.75% by weight of platinum, 0.35% by weight of chlorine and 0.35% by weight of fluorine. The catalyst was disposed in the reaction zone in three individual beds, having suitable internal heating elements therebetween. The reaction zone was maintained under an imposed hydrogen pressure of 500 pounds per square inch, and the

charge stock passed therethrough at a liquid hourly space velocity of 1.0. The liquid charge was admixed with hydrogen in an amount to yield a hydrogen to hydrocarbon mole ratio of 10.0; the operating temperature of the catalyst disposed within the reaction zone was adjusted to yield a normally liquid product effluent having an octane rating in excess of about 100.0, F-1 Clear. The operation was continued over a period of about 30 days until the catalyst life had attained a level of about 25.0 barrels per pound. The charge stock was a semi-heavy naphtha having an octane rating, F-1 Clear, of 36.0, and of which less than 5.0% by volume was distillable at a temperature below 212° F. Various properties of the charge stock are given in the following Table I, along with the properties of the catalytically reformed effluent obtained as a composite sample from the entire period of operation.

TABLE I

Properties of Charge Stock and Reformed Product

	Charge	Product
Gravity, ° API @ 60° F.	59.3	45.4
100 MI. ASTM Distillation, ° F.		
Initial Boiling Point	203	118
5%	221	
10%	226	153
30%	243	191
50%	261	240
70%	282	263
90%	309	303
95%	318	
End Boiling Point	348	400
Vol. Percent @ 212° F.	5.0	38.5
Hydrocarbon Type Analysis, Vol. Percent:		
Paraffins	71	
Olefins	Tr.	
Naphthenes	19	
Aromatics	10	164.0
Octane, Ratings:		
F-1 Clear	36.0	100.5
F-1+3 cc. TEL/gal.	64.8	¹ 103.8

¹ 18.3 vol. percent toluene.² 1.5 cc. TEL/gal.

It should be noted, from the data presented in the foregoing Table I, that although the octane rating of the liquid product effluent is entirely satisfactory, being 100.5, the volatility requirement falls far short of the required specification, being only 38.5% distilled at a temperature of 212° F.

The catalytically reformed liquid product effluent was fractionated at cut-points of 88.5° C. and 116° C., to provide "pre-toluene," "toluene," and "post-toluene" fractions. The various properties of the "pre-toluene" and "toluene" fractions are given in the following Table II, along with the properties obtained upon the blended product.

TABLE II

Properties of Blending Fractions and Blended Products

Cut-point, ° C.	88.5	116
Vol. Percent of Reformed Product	35.4	18.6
Aromatics, Vol. Percent	8.1	82.7
Toluene, Vol. Percent	0.9	70.7
Vol. Percent in Blended Product	23.7	76.3
Properties of Blended Product:		
Gravity, ° API @ 60° F.	46.1	
ASTM 100 MI. Distillation, ° F.		
IBP	126	
5%	163	
10%	187	
30%	207	
50%	219	
70%	229	
90%		
95%		
End Point	259	
Vol. Percent @ 212° F.	57.5	
Octane Ratings:		
F-1 Clear	100.5	
F-1+1.5 cc. TEL/gal.	106.6	
Aromatics, Vol. Percent	65.0	
Toluene, Vol. Percent	54.0	

It should be noted that the fractions were blended in a volumetric ratio of 23.7 to 76.3, which is substantially less than the 35.4 to 18.6 ratio in which they were initial-

ly present in the reformed product. From the properties of the blended product, it is noted that the octane rating is substantially the same, being 100.5 F-1 Clear, and that the response to tetra-ethyl lead has increased from 103.8 to 106.6. However, it must also be noted that the volatility factor, that is, the volume percent distillable at a temperature below 212° F. has increased to 57.5, which figure far exceeds the minimum required.

The foregoing specification and example clearly indicate the method of the present invention, and illustrate the benefits to be afforded through the utilization thereof.

I claim as my invention:

1. A process for producing a gasoline having an F-1 Clear octane rating in excess of about 98.0, at least 45.0% by volume of which is distillable at a temperature below 212° F., which process comprises fractionating a debutanized catalytically reformed product of which less than 45.0% by volume is distillable at a temperature of 212° F., into a first fraction obtained at a cut-point within the

range of about 85° C. to about 90° C. and substantially free from toluene, a second fraction obtained at a cut-point within the range of about 110° C. to about 120° C. and containing substantially all the toluene initially present in said debutanized reformed product, and a third bottoms fraction higher boiling than toluene; combining a portion of said first fraction with a portion of said second fraction in a volumetric ratio less than that in which they were initially present in said catalytically reformed product and such that the resulting mixture has an octane rating, F-1 Clear, greater than 98.0 and at least 45.0% by volume of which is distillable at 212° F., and combining the remainder of said first and second fractions with said third bottoms fraction to yield a high octane blending stock of which less than 45.0% by volume is distillable at a temperature of 212° F.

2. A combination process for producing high octane gasoline of which at least about 45.0% by volume is distillable at a temperature below 212° F., which comprises catalytically reforming a low octane hydrocarbon mixture of lower volatility, at reforming conditions selected to produce a liquid reformed product having an octane rating, F-1 Clear, in excess of about 98.0, of which less than about 45.0% by volume is distillable at a temperature of 212° F., fractionating said catalytically reformed product

into a first fraction lower boiling than toluene and obtained at a cut-point less than about 90° C., a second toluene fraction obtained at a cut-point less than about 120° C. and a third bottoms fraction higher boiling than toluene; combining a portion of said first fraction with a portion of said second fraction in a volumetric ratio less than that in which they were initially present in said catalytically reformed product and such as to yield a high octane mixture of which at least about 45.0% by volume is distillable at a temperature below 212° F., and combining the remainder of said first and second fractions with said third bottoms fraction to yield a high octane blending stock of lower volatility.

3. The process of claim 2 further characterized in that said first fraction is substantially free from toluene, and said second fraction contains substantially all the toluene initially present in said catalytically reformed product.

4. The process of claim 2 further characterized in that said first fraction is obtained at a cut-point within the range of about 85° to about 90° C., and said second fraction is obtained at a cut-point of from about 110° C. to about 120° C.

5. A combination process for producing a gasoline having an F-1 Clear octane rating in excess of about 98.0, at least 45.0% by volume of which is distillable at a temperature of 212° F., which process comprises catalytically reforming a low-octane hydrocarbon mixture of lower volatility, at reforming conditions selected to produce a liquid reformed product having an octane rating, F-1 Clear, in excess of about 98.0 of which less than 45.0% by volume is distillable at a temperature of 212° F., frac-

tionating said reformed product into a first fraction, obtained at a cut-point within the range of about 85° C. to about 90° C. and substantially free from toluene, a second fraction obtained at a cut-point within the range of about 110° C. to about 120° C. and containing substantially all the toluene initially present in said reformed product, and a third bottoms fraction higher boiling than toluene; combining a portion of said first fraction with a portion of said second fraction in a volumetric ratio less than that in which there were initially present in said catalytically reformed product and such that the resulting mixture has an octane rating, F-1 Clear, in excess of about 98.0, of which at least 45.0% is distillable at 212° F., and com-

5
10

bining the remainder of said first and second fractions with said third fraction to yield a high-octane blending stock of which less than about 45.0% is distillable at a temperature of 212° F.
